TUBING HEAD AND BLOW-OUT
PREVENTER

Granville A. Humason, Houston, Tex.

Application November 21, 1932, Serial No. 643,605

2 Claims. (Cl. 166—14)

This invention relates to a tubing head and blowout preventer.

An object of the invention is to provide novel means for forming a fluid tight joint between an outer casing and an inner pipe in a well bore, and comprehends also novel means for anchoring the inner pipe in the well and securing it against being blown out by gas pressure in case strong internal pressure is encountered in the well.

10 The invention also comprehends a novel type of pressure head with novel means for securing the same about the inner pipe and for anchoring the same to the outer casing.

15 The invention also embodies novel means for connecting the inner pipe to the outer casing and which is of such construction as to adapt it for use generally for connecting pipe and the like.

With the above and other objects in view, the invention has particular relation to certain novel 20 features of construction, operation and arrangement of parts, an example of which is given in this specification and illustrated in the accompanying drawings wherein:

Figure 1 shows a side view of the tubing head 25 partly in section.

Figure 2 shows a cross sectional view, taken on the line 2—2 of Figure 1.

Figure 3 shows a cross sectional view taken on the line 3—3 of Figure 1.

30 Figure 4 shows a side view, partly in section, of another form of the apparatus taken on the line 4—4 of Figure 5.

Figure 5 shows a cross sectional view taken on the line 5—5 of Figure 4, and

35 Figure 6 shows a cross sectional view taken on the line 6—6 of Figure 4.

Referring now more particularly to the drawings, wherein like numerals of reference designate similar parts in each of the figures, the numeral 1 designates an outer pipe as, for example, a casing in a well bore and to the upper end of which is attached a tubular head, as for example, a casing head 2. Around the head 2 there is a turnable lock sleeve 3 which is supported on an external shoulder 4 of said head. The sleeve 3 has an internal annular channel 5, forming a keyway and opposite this channel there are the vertical external seats 6 around the head 2. In said seats 6 there are rollers as 7 which form keys to prevent the detachment of the lock sleeve 3 from the head 2 and which serve also as anti-friction means to provide for the easy rotation of the sleeve. The keys or rollers 7 may be inserted into place, in assembling the sleeve 3 on the head, through the oblong opening 8, through

the sleeve 3, as said sleeve is turned, and when said keys or rollers 7 are all inserted into their respective seats, the opening 8 may be closed by the closure plate 9 secured in place in any selected manner as by set screws 10.

5 The lock sleeve 3 has an inside annular channel 11 leading upwardly from which are the ways 12.

The numeral 13 designates an inside pipe, which is connected to a suitable tubular hanger 14, and this hanger is provided with the external spaced lugs 15.

When the inner pipe 13 is lowered into the well, the lugs 15 may pass through the ways 12 and land on the upper end of the head 2 and the locking sleeve 3 may then be turned so as to carry the ways 12 out of alignment with the lugs 15 and to locate said lugs 15 in the groove 11 so as to thereby lock the hanger 14 and the inner pipe 3 to the casing head.

It will be noted that the upper end of the head 2 has an inside groove or channel 16 and the hanger 14 has an external annular shoulder 17 which seats in said channel or groove 16 of said casing head. Beneath the shoulder 17 the hanger 14 is reduced so as to fit snugly within the casing head 2 and leading upwardly from the lower end of said reduced portion there is an annular row of ducts 18.

Counter sunk into the reduced portion of the hanger 14 there is an annular packing member 19 which has an annular internal chamber 20 therein, into which said ducts 18 lead.

The construction hereinbefore described will 35 form a fluid tight joint between the inner pipe 13 and the casing 1. The fluid, under pressure, in the well may flow out through the pipe 13, and be led off through the flow line 21. The gas accumulating in the well outside of the pipe 13 may be relieved through outlets 22 into which suitable 40 valve controlled lines will be connected.

When a well is equipped with a tubing head of the character above described, the inner pipe 13 will be securely locked in place in case of a blowout and a fluid tight joint will be formed 45 between said inner pipe and the casing head and the oil or other liquid flowing through the pipe 13 as well as the gas accumulating in the casing and may be readily led off and controlled.

The sections of the flow line may be connected 50 by a fluid tight joint similar to the construction, hereinabove described, for connecting the casing 1 to the inner pipe, wherein the numeral 23 designates a coupling member corresponding to the casing head 2 and connected to one of the sec- 55

tions of the line 21, and the numeral 24 designates a coupling member, corresponding to the hanger 14 and connected to another section of the line 21. These coupling members 23, 24 are connected by the locking sleeve 3, in the manner hereinbefore described and the packing member 19 forms a fluid tight joint between them.

Referring to the construction shown in Figures 4 to 6 inclusive, there is a hanger 14' mounted in the casing head 2 in a manner similar to the hanger 14 illustrated in Figure 1 and there is a fluid tight joint formed between the lower end of the hanger 14' and the casing head 2 by means of the packing 19 which surrounds the reduced lower end of said hanger 14' and which has an internal chamber 20 with the annular row of ducts 18 leading downwardly therefrom through the lower end of said hanger 14'. The hanger 14' has an internal upwardly flared seat 25 in which there is mounted a pressure head 26. This head tapers downwardly to conform to the shape of and to fit closely within said seat 25 and is formed of corresponding, complementary, confronting sections hinged together at their upper ends by means of the hinge 27. The mid-portion of the pressure head may be formed of resilient material such as rubber, forming a packing 28 having an internal annular chamber 29 with the ducts 30 leading downwardly therefrom and communicating with the annular space 31 around the inner pipe 13 and between it and the lower end of the pressure head. The gas pressure thus accumulating in the casing outside of the inner pipe 13 may enter the chamber 29 and expand the packing 28 forming close joints between the pressure head and the seat 25 as well as between the pressure head and the inner pipe 13. The pressure head 26 is composed, with the exception of the packing 28, of suitable metal having the internal downwardly pitched teeth 31 and upwardly pitched teeth 32 to engage and hold the inner pipe 13. The pressure head, in application to the pipe 13, may be opened and latched around said pipe. Latch means is provided by forming a mortise 35 in one section of the head into which a tenon 34 of the other section may fit when the head is closed about the inner pipe. There is a spring seated dog 35 arranged to project into a recess 36, in said tenon, to latch the parts in closed position about the inner pipe 13. This dog is slidably mounted in the other section of the head and may be released by inserting a suitable implement through the slot 37 of said last mentioned section and into a hole 38 of said dog whereby the dog may be released and the sections of the pressure head swung open on the hinge 27. At the lower end of the pressure head each section is provided with an external dovetailed keyway 39 and in these keyways the arcuate dovetailed keys 40 are fitted and when the sections of the pressure head are latched about the inner pipe the keys 40 may be moved about

said keyways into position to break the joints between the sections of the pressure head and thus securing the lower ends of the sections of the pressure head together. When the pressure head has been secured about the inner pipe said inner pipe may then be lowered to carry the pressure head into the seat 25 of the hanger 14'. 5

The upper end of the hanger 14' has the external annular groove 41 with the oppositely arranged gates or ways 42, leading outwardly therefrom. There is a retainer cap 43 whose lower end has the inwardly extending lugs 44. This retainer cap has a side opening 45 so that it may be passed about the pipe 13 above the hanger 14' and the lugs 44 aligned above the gates 42 and 10 the retainer cap then lowered and turned so as to carry the lugs 44 around into the groove 41 whereby said retainer cap 43 will be locked in place and in turn will lock the pressure head 41 securely in the hanger 14'. 20

The drawings and description disclose what is now considered to be a preferred form of the invention by way of illustration only, while the broad principle of the invention will be defined by the appended claims. 25

What I claim is:

1. In combination a casing head, a hanger therein having an upwardly flared seat, a sleeve rotatably mounted on the head, interengaging means carried by the sleeve and hangers respectively arranged to be interengaged or released by appropriate turning movements of the sleeve, anti-friction means between the sleeve and head arranged to lock the sleeve against detachment from the head, packing means between the hanger and head, a pressure head adapted to fit into said seat and to surround the pipe, said pressure head being composed of confronting sections whose upper ends are hinged together at one side, the midportion of said head being 30 formed of resilient packing material, one section of the pressure head having a mortise and the other section having a tenon adapted to fit into said mortise, a spring seated dog on one section of the pressure head adapted to engage the tenon 40 to lock said sections together about said pipe and a retainer cap detachably secured to the hanger and engageable with the upper end of the pressure head. 35

2. In apparatus of the character described, a 50 downwardly tapering pressure head formed of complementary confronting sections, arcuate in cross sectional contour and hinged together at one side, each section of said pressure head having an external keyway, said keyways being in 55 alignment, arcuate keys fitted in said keyways, means for latching said sections about a pipe, said keys being movable about the keyways into position to break the joints between the sections when the sections are latched together. 60

GRANVILLE A. HUMASON.
